UNITED STATES PATENT OFFICE

2,132,264

CONTROL SYSTEM

William R. King, Schenectady, N. Y., assignor to
 General Electric Company, a corporation of
 New York

Application February 1, 1936, Serial No. 61,937

5 Claims. (Cl. 172—240)

This invention relates to control systems, more particularly to systems for controlling the actuation of reciprocating loads, and it has for an object the provision of a simple, reliable, efficient and improved system of this character.

More specifically, the invention relates to control systems for vibrating screens and the like in which the coil that actuates the load is supplied with a periodically varying voltage from an electric valve which in turn is supplied from a source of alternating voltage. In most industrial areas the frequency of the voltage supply has some fixed value, such for example as sixty cycles. In the absence of any special control apparatus, a valve energized from such a source would deliver sixty current impulses per second to the coil which in turn would deliver sixty impulses to the load. For certain applications, it is often desirable to cause the coil to deliver a lesser number of impulses to the load, such for example as thirty, twenty or fifteen impulses per second. Commutator devices and synchronous switches have previously been utilized for producing low frequency voltage, but such devices are expensive, require costly maintenance and in general leave much to be desired. Accordingly, a further object of this invention is the provision of a control system of this character for controlling an electric valve to pass the desired low frequency current impulses to the actuating coil and in which the control is carried out entirely by means of stationary elements and apparatus.

In carrying the invention into effect in one form thereof, an electric valve having an anode, cathode and control electrode is connected between a source of alternating voltage and the actuating coil. An energy storage device, for example, a capacitance, is connected across the output circuit of the valve with a connection to the control electrode. When the valve passes current to the coil during a positive half cycle of the anode voltage, the capacitance becomes charged and applies a negative voltage to the control electrode which maintains the valve non-conducting. Means are provided for discharging the energy storage device at a predetermined rate so that the valve is again rendered conducting after an interval of one or more positive half cycles, as desired.

50 In illustrating the invention in one form thereof, it is shown as embodied in a system for controlling the actuating coil for a vibrating screen or the like.

For a better and more complete understanding 55 of the invention, reference should now be had to

the following specification and to the accompanying drawing in which Fig. 1 is a simple diagrammatical illustration of an embodiment of the invention and Fig. 2 is a chart of characteristic curves explaining the operation of the invention.

Referring now to the drawing, one terminal of a magnet coil 10, such for example as the shaker magnet of a vibrating screen, is connected to one side of a suitable source of alternating voltage represented by the supply lines 11, 12. An electric valve 13 is interposed in the connections between the opposite terminal of the magnet coil 10 and the side 12 of the supply source. As shown, the anode 13a of the valve is connected to the side 12 of the supply source and the cathode 13c is connected through conductors 14 and 15 to the opposite terminal of the magnet coil 10. The valve is also provided with a control electrode or grid 13b which serves to control the passage of current between the cathode and the anode.

Although the valve 13 may be of any suitable type, it is preferably of the three or four-electrode type, into the envelope of which a small quantity of an inert gas such for example as mercury vapor is introduced after exhaust. The presence of this gas within the envelope serves to convert the usual pure electronic discharge into an arc stream thereby constituting the valve an electrostatically or grid controlled arc rectifier.

In valves of this type, current will flow between the anode and the electrode during that half cycle of the applied voltage in which the voltage of the anode is positive with respect to the voltage of the cathode, provided the voltage of the grid is more positive than a predetermined critical value necessary to initiate the current flow.

Once current has started to flow, between the anode and cathode, the grid does not readily control the magnitude of the current flowing in the output circuit. Consequently, the current flow in the output circuit can only be stopped by interrupting the anode circuit or reducing the anode voltage to zero. For the purpose of supplying a voltage to the grid sufficiently positive

to initiate the flow of current between the anode and cathode, a transformer 16 is provided, the primary winding 16a of which is connected across the supply line 11, 12. This transformer has a plurality of secondary windings 16b, 16c and 16d.

One terminal of a capacitance 17 is connected through a protective resistance 18 to the grid 13b and the opposite terminal of this capacitance is connected through variable resistance 19 and resistance 20 to the cathode 13c. The terminals of the secondary winding 16b are connected across

the capacitance 17 and a resistance 21 connected in series relationship therewith so that an alternating voltage is introduced into the grid or input circuit of the electric valve 13. Energy for heating the cathode 13c to the required degree of incandescence is supplied from the secondary winding 16a to which the heating filament of the cathode is connected as illustrated.

As thus far described, the electric valve 13 would become conducting once during each cycle of the alternating voltage of the source 11, 12 and would pass an impulse of current to the magnet coil 10 once during each cycle. Since it is desired to pass a lesser number of current impulses through the magnet coil than the number of cycles of the voltage of the source, means are provided for rendering the valve non-conducting during one or more subsequent positive half cycles of the applied voltage. To this end, an energy storage device, illustrated as a capacitance 22, is connected from the cathode 13c to the side 11 of the supply source through a rectifier 23 and a resistor and is also connected to the common connection between the resistance 21 and the capacitance 17 which is connected to the grid 13b. Thus, the capacitance 22 is connected from the cathode 13c to the grid 13b. When the valve 13 is conducting during a positive half cycle of anode voltage, the capacitance 22 becomes charged and applies a negative voltage to the grid 13b so that during the following positive half cycle of anode voltage, the voltage of the grid is maintained more negative than the critical grid voltage. As a result, the valve 13 does not conduct current during the following positive half cycle of anode voltage. In order to render the valve conducting after one or more positive half cycles of anode voltage, as desired, means are provided for discharging the capacitance 22 at a predetermined rate. These means are illustrated as resistances 19, 20 connected in parallel with the capacitance 22.

In order to prevent the discharge of the capacitance 22 by the reverse voltage across the coil 10, the rectifier 23 is included in the connections between the capacitance 22 and the side 11 of the supply source. Although the rectifier 23 may be of any suitable type it is preferably a vacuum tube having anodes 23a and a hot cathode 23b which is heated to the required degree of incandescence by means of energy supplied from the secondary winding 16c to which the cathode is connected as illustrated.

With the foregoing understanding of the elements and apparatus and their organization in the completed system, the operation of the system itself will be readily understood from the following detailed description.

In Fig. 2, the alternating voltage of the source 11, 12 is represented by the sinusoidal curve 24 in which ordinates above the axis O—O represent positive values of voltage and ordinates below the axis O—O represent negative values of voltage. The voltage supplied to the grid circuit through the secondary winding 16b of the transformer is represented by the light sinusoidal curve 25. Preferably the voltage represented by the curve 25 leads the voltage 24 by an angle determined by the constants of the capacitance 17 and the resistance 21. However, for the purpose of simplicity, this voltage is shown and described as in phase with the anode voltage. The critical grid voltage of the electric valve 13 is represented by the dotted curve 26. If the voltage of the grid remains less positive, i. e. more nega-

tive than this critical grid voltage throughout the positive half cycle of anode voltage the valve 13 will not conduct. If at any instance this critical grid voltage is exceeded the valve 13 will become conducting and will continue to pass current during the remainder of the positive half cycle of applied voltage and as long thereafter as the anode remains positive.

Thus, since the grid voltage of the valve 13 becomes more positive than the critical value at the beginning of the first positive half cycle of the anode voltage 24, the valve 13 becomes conducting and a pulse of current represented by the heavy curve 27 flows through the magnet coil 10. When the anode voltage 24 passes through zero, the current 27 would ordinarily tend to stop flowing, but owing to the inductance of the coil 10 the current continues to flow until a time T_1 during the negative half cycle of voltage. At this point the current flow through the coil ceases.

As the current through the coil 10 builds up, the capacitance 22 becomes charged with the polarity indicated in the drawing so that a negative voltage represented by the curve 28 is applied to the grid 13b. Now the actual grid voltage is the algebraic sum of the voltage represented by the curve 25 and the voltage represented by the curve 28 and is represented in Fig. 2 by the undulating curve 29. When the capacitor 22 attains its maximum potential, the charge begins to leak off as represented by the upward slope of the curve 28 at a rate depending upon the ohmic value of the resistances 19 and 20.

During the second positive half cycle of the anode voltage 24, the actual grid voltage 29 at no time exceeds the critical grid voltage 26 and consequently the valve 13 remains non-conducting during the entire second positive half cycle of anode voltage. However, during the third positive half cycle of anode voltage, the actual grid voltage becomes more positive than the critical grid voltage and consequently the valve 13 again becomes conducting and passes a second impulse of current through the magnet coil 10 and thereafter the previously described operation is repeated. Thus, it will be seen that the valve 13 only becomes conducting during every other positive half cycle of anode voltage and therefore, if the frequency of the voltage of source 11, 12 is of some commercial value such for example as sixty cycles, the frequency of the current impulses through the coil 10 will be thirty impulses per second.

By varying the value of the resistance 19, the rate of discharge of the capacitance 22 can be still further decreased, and the number of current impulses per second still further reduced. In practice, the number of current impulses has been reduced to one impulse for every thirty positive half cycles of anode voltage, although there was no indication that this was the limit.

When the voltage passes through zero at the end of a positive half cycle in which the valve 13 is conducting the voltage across the magnet coil 10 reverses. This voltage reversal would discharge the capacitance 22 if it were not for the rectifier 23 which prevents passage of current in such a direction as to discharge the condenser.

It will sometimes be found advantageous to advance the AC grid voltage represented by the curve 25 a substantial phase angle ahead of the anode voltage in order to insure that the valve 13 will fire as early in the cycle as possible during those positive half cycles of anode voltage in which the valve is to conduct. As previously

pointed out, this is effected by means of the capacitance 17 in the grid circuit.

It will also sometimes be found advantageous to substitute for transformer secondary winding 16b a secondary winding on a separate transformer of the type commonly known as a peaking transformer. The peaked voltage wave obtained from the secondary of this transformer will further insure that the valve 13 will fire as early in the cycle as possible during those half cycles of anode voltage in which the valve is to conduct.

Although in accordance with the provisions of the patent statutes, this invention is described as embodied in concrete form, it will be understood that the elements and apparatus are merely illustrative and that the invention is not limited to the exact arrangement shown in the drawing since alterations and modifications will readily suggest themselves to persons skilled in the art without departing from the true scope of the invention or from the scope of the annexed claims.

What I claim as new and desire to secure by Letters Patent of the United States is:

1. A control system for a reciprocating load comprising a coil for operating said load, means for supplying a periodically varying voltage comprising an electric valve connected between a source of periodically varying voltage and said coil, and having an anode, cathode and control grid, means for supplying a voltage more positive than a predetermined critical value to said grid during a positive half cycle of the voltage of said source thereby to energize said valve to pass current, and means for maintaining the voltage of said grid more negative than said critical value during a succeeding positive half cycle thereby to render said valve non-conducting comprising a capacitance connected across said cathode and grid and having a connection to one terminal of said coil and a rectifier in said connection for preventing discharge of said capacitance by reversal of voltage of said coil.

2. A control system for reciprocating load comprising a coil for operating the load, means for supplying a periodically varying voltage to said coil comprising an electric valve connected between said coil and a source of voltage of predetermined frequency and having a cathode, anode and control grid and means for controlling the frequency of the voltage applied to said coil comprising a capacitance connected across said cathode and grid and having a connection to said coil, a resistance connected in parallel with said capacitance for controlling the rate of discharge thereof, and a rectifier included in said connection for preventing discharge of said capacitance by reversal of the voltage of said coil.

3. A control system for a reciprocating load comprising a coil for operating said load, means for supplying a periodically varying voltage to said coil comprising an electric valve having an anode connected to a source of alternating voltage, a cathode connected to one terminal of said coil and a control grid, connections from said

source to said grid so that the voltage of said grid is more positive than a predetermined critical value during a half cycle when the anode voltage is positive thereby to render said valve conducting, means for controlling the frequency of the voltage supplied to said coil comprising a capacitance connected from said cathode to said grid and having a connection to the other terminal of said coil to maintain the voltage of said grid more negative than said critical value during a succeeding positive half cycle of anode voltage thereby to render said valve non-conducting, and a resistance connected in parallel with said capacitance to control the rate of discharge thereof, and a rectifier in said connection for preventing the discharge of said capacitance by reversal of the voltage of said coil.

4. A control system for a reciprocating load comprising a coil for operating the load, means for supplying a periodically varying voltage to said coil comprising an electric valve having an anode, a cathode and control grid, means for controlling the frequency of said voltage comprising means for supplying an alternating voltage to said grid, an energy storage device connected across said cathode and control electrode and having a connection to one terminal of said coil, and means for advancing the phase relationship of the alternating component of the grid voltage relative to the anode voltage to insure energization of said valve substantially at the beginning of a positive half cycle of anode voltage.

5. A control system for a reciprocating load comprising a coil for operating the load, a source of alternating voltage of predetermined frequency, means for supplying a periodically varying voltage of reduced frequency to said coil comprising an electric valve having an anode connected to said source, a cathode connected to one terminal of said coil, and a control grid, connections from said source for supplying an alternating voltage to said grid so that the grid voltage is more positive than a predetermined critical value when the anode voltage is positive thereby to energize said valve to conduct current, a capacitance connected from said cathode to said grid and having a connection to the opposite terminal of said coil for maintaining the voltage of said grid more negative than said predetermined value during the following positive half cycle of anode voltage thereby to render said valve non-conducting, a rectifier included in said connection for preventing discharge of said capacitance by reversal of the voltage of said coil, a resistance connected in parallel with said capacitance for controlling the discharge of said capacitance to render said valve conducting during a subsequent positive half cycle at anode voltage, and a capacitance included in circuit with said grid for insuring energization of said valve at approximately the beginning of a positive half cycle of said anode voltage.

WILLIAM R. KING.
